UNITED STATES PATENT OFFICE.

WALTER S. JOHNSON, OF SEATTLE, WASHINGTON.

PACKING-CASE.

1,260,390.

Specification of Letters Patent. Patented Mar. 26, 1918.

Application filed April 9, 1917. Serial No. 160,652.

To all whom it may concern:

Be it known that I, WALTER S. JOHNSON, a citizen of the United States, residing at Seattle, in the county of King and State 5 of Washington, have invented certain new and useful Improvements in Packing-Cases, of which the following is a specification.

This invention relates to improvements in protective cases for egg-containing car- 10 tons in retail delivery to the purchaser.

One of the objects of the invention is the provision of a case of simple construction that will protect the contents of an egg- 15 carton from injury while being delivered to the customer, including devices for releasably retaining the carton within the case.

A further object of the invention is the provision of simple and efficient means whereby an egg-carton may be readily in- 20 serted in a case or withdrawn therefrom.

The invention consists in the novel construction of an egg-carton containing case, as will me hereinafter described and claimed.

In the accompanying drawings, showing 25 the preferred form of my invention, Figure 1 is a view in horizontal section of a packing case embodying my invention. Fig. 2 is a longitudinal vertical section thereof with an egg-carton contained therein, and 30 Fig. 3 is a view partly in front elevation and partly in transverse section of the same.

The present invention is designed for the purpose of carrying an egg-carton consisting, usually, of a box C made of paper or the like and divided interiorly into individual egg receptacles by means of a filler, so-called, formed of inter-engaging longitudinal and transverse partitions F and F'.

To these ends, I provide a case comprising 40 side walls 2 and 3, top and bottom walls 4 and 5, and a rear end wall 6. The front end of the case is open for the insertion or removal of the carton. Said side walls are recessed, as at 7, to afford at inside corners of the case projecting strips 8 which are provided with rabbets 9 to accommodate the side corners of the carton.

The top and bottom of the case are also 50 provided with recesses, such as 10, which are most advantageously afforded by longitudinal partition cleats 11 secured, as by being glued, in grooves 12 provided therefor in the respective walls. Said partition

cleats are disposed to be directly above and 55 below the longitudinal filler partitions F.

At the rear, vertical strips 13 are em- 60 ployed at each side, as shown in Figs. 1 and 2, to furnish stops against which the carton is brought when shoved into the case, and 65 also providing a recess 14 at the rear end of the case. At the front, or mouth, of the case, the various partition cleats 11 are sloped, as at 11¹, and the outer end of the rabbets are formed to provide flaring surfaces 9¹, 65 whereby the introduction of a carton is fa- cilitated.

Secured to the inner surface of the case- 70 side 3 is the longitudinally disposed shank 15 of a spring-metal latch having near its forward end a bill 16 arranged to engage over the outer end of a carton, as indicated by broken lines C¹ in Fig. 1, to releasably retain the same within the case.

The extremity of the spring is inclined 75 as at 17, whereby a carton, upon being in- serted in the case, will thrust the latch- 80 bill out of the path of the carton. To ac- commodate the outward movements of the spring, the side wall 3 is provided with a slot 18 and a thumb-receiving recess 19. The spring-latch, however, is adapted to occupy the position substantially as repre- 85 sented by full lines in Fig. 1, so that when a carton is engaged thereby, the latter will be pressed against the opposing walls of the rabbets 9 in the projections 8 of the wall thereby obviating any relative move- 90 ment of the carton with respect to the case during transportation, or otherwise.

In operation, the carton C is introduced 95 within the packing case by being inserted through the open end of the latter and in so doing engages the inclined portion 17 of the latch, causing the latter to yield. When the carton has been inserted to abut 100 the strips 13, the carton will have passed beyond the latch-bill 16 which will there- upon be protruded inwardly to secure the carton from being accidentally withdrawn, and at the same time the latch-part 21 will 105 press against the carton to thrust the same toward the opposite side wall of the case to prevent the carton from having any relative movement with respect to the case.

The rabbeted corner projection 8 sup- 105 ports the carton side walls, and the cleats 11 support the carton in the planes of their

longitudinal partitions F. The top and bottom walls of the carton are unsupported at the respective egg receptacles there-in and enable the eggs to be contained 5 within the carton without damage.

To remove the carton from the case, the latch is retracted by disengaging the bill 16 thereof by means of the operator's finger, and pushing the carton outwardly with 10 a finger of his other hand inserted through an aperture 20 provided in the end wall 6.

The invention is intended for employment by retail grocers and others in delivering eggs to purchasers, and insures 15 that the goods will reach the customer in undamaged condition. The egg-filling cartons are placed in the packing case at the store, and can be handled without danger of breaking. After the carton is 20 ejected at the place of delivery, the case is returned to the store for further use.

While I have described my invention with some particularity, I do not intend that my invention shall be restricted to the precise 25 details illustrated and described, as the same may be modified in various ways to carry out the spirit of the invention and within the scope of the appended claims.

Having described my invention, what I 30 claim, is—

1. A packing case comprising a box body having at top, bottom side and an end wall, spaced cleats extending longitudinally of the top and bottom wall and projecting beyond the inner surfaces thereof, the side 35 walls being provided at their upper and lower edges and at their surfaces with transversely thickened portions having longitudinally disposed rabbets and vertical strips lo-

cated at the end portions of the end wall 40 and between the thickened portions of the side walls and having side surfaces which lie in the same vertical plane as that in which the vertical rabbets at the opposite ends thereof lie, the parts being so arranged that the major portions of the surfaces the sides and end of a carton will be held by the cleats, rabbets and strips spaced from the inner surfaces of the box body 45 when the carton is inserted in the same.

2. The combination with an egg carton having longitudinal partitions affording egg retaining spaces therebetween, of a packing case for protecting the contents of said carton, including side, top and bottom walls and one end wall, and longitudinal strips provided on said top and bottom walls and disposed in vertical planes with the respective partitions.

3. The combination with an egg carton having longitudinal partitions affording egg retaining spaces therebetween, of a packing case for protecting the contents of said carton, including side, top and bottom walls and one end wall, longitudinal strips provided on said top and bottom walls and disposed in vertical planes with the respective partitions, and a yielding latch mounted upon one of said walls and arranged to retain said carton within said case and to resiliently urge the carton toward the end wall of the case.

Signed at Seattle, Washington, this 2nd day of April, 1917.

WALTER S. JOHNSON.
